Application August 4, 1955, Serial No. 526,420

5 Claims. (Cl. 250—103)

My invention relates to a device for controlling the potential of a high-voltage source.

More specifically, my invention relates to a device for controlling the potential of a source employing secondary X-radiation produced by exposing samples of chemical elements to primary X-radiation produced by an X-ray tube connected to the source of potential which is subject to control.

Every element of the periodic series emits characteristic secondary X-radiation when exposed to a primary beam of X-radiation of sufficiently short wave length. If the spectrum of the primary X-radiation contains wave lengths shorter than the absorption edge of that element, the intensity of its characteristic radiation will increase rapidly as the intensity of the primary radiation at those wave lengths increases. Thus, by utilizing characteristic secondary X-radiation rather than primary X-radiation, it is possible to control the voltage of a source within narrow limits.

It is accordingly a principal object of my invention to provide a novel apparatus for controlling the potential of a voltage source by means of the characteristic secondary X-radiation produced by an element exposed to primary radiation having a wave length below the absorption edge of that element.

It is a further object of my invention to provide a novel apparatus for controlling the potential of a voltage source within narrow limits.

These and further objects of my invention will appear as the specification progresses.

In accordance with my invention, I expose a sample containing at least one element to primary X-radiation produced by a tube energized by the voltage source the potential of which is to be stabilized. This element is selected so that the primary X-radiation from the tube will excite at least one element in the sample to emit its characteristic spectrum. The sample may also contain a second element so low in atomic number that its characteristic lines are totally absorbed in air, or sufficiently higher in atomic number that no characteristic lines are excited which can be detected. These samples will hereinafter be referred to as "secondary radiators" since they produce secondary or characteristic X-radiation upon exposure to primary X-radiation from the tube.

As the voltage applied to the X-ray tube varies, the intensity of the characteristic X-radiation of the first element will vary as the square of the difference in applied voltage while the second element only will scatter the primary radiation. Thus, by suitably detecting and converting the X-radiation produced by the respective elements into appropriate electrical quantities, corrective measures can be taken to compensate for the variations in potential of the source.

The invention will be described in connection with the accompanying drawing which shows a voltage stabilizing device according to the invention.

In the embodiment of the invention shown in the drawing, cathode 1 and anode 2 of an X-ray tube 3, which

2

serves as a source of primary X-radiation for the invention as well as other purposes, are connected to a line source of voltage 4 through a transformer 5.

In the path of a portion 9 of the X-radiation, I expose 5 secondary radiators 10 and 11 of, for example, silver and molybdenum respectively, which emit secondary X-radiation when exposed to the primary X-radiation. The molybdenum will not emit its characteristic X-radiation if the voltage applied to the X-ray tube is less than 20 10 kv. Any increase in voltage above 20 kv. applied to the tube will cause the intensity of molybdenum characteristic radiation (MoK α) to increase at a rate proportional to the square of the difference between the applied voltage and 20 kv. whereas at that voltage the silver will only scatter the broad spectrum X-radiation whose intensity increases only slightly as the voltage applied to the tube increases above 20 kv. Thus, an increase of 2 kv. in the voltage applied to the X-ray tube will result in a 100% increase in intensity of the MoK α radiation 20 and a 5% increase in the X-radiation from the silver sample.

A portion of this characteristic X-radiation of the two 25 secondary radiators is intercepted by collimators 12 and 13 respectively and is directed into detectors 14 and 15 respectively. These detector are shown as conventional Geiger-Muller tubes having a central anode 16 and a concentric cathode 17, connected to a source of high voltage, the tube being filled with an ionizable medium. Alternatively, a scintillation counter, proportional counter, 30 ionization chamber or similar detection device which will convert X-ray quanta into electrical pulses, may be used. The outputs of the detectors are shown connected to a conventional bridge circuit 18 for deriving an electrical quantity proportional to the difference in outputs of the 35 respective detectors. Connected between the mid-points of the bridge is an electric motor 19 mechanically coupled to the moveable arm of a variable autotransformer 20 in the line source. Alternatively, a conventional error-correcting system connected to the outputs of the detectors could be employed to compensate for variations in line voltage.

Any element of the periodic table may be employed 40 as a secondary radiator to control the voltage applied to the tube. At higher operating potentials, heavier elements such as uranium which emits its characteristic radiation only when the potential applied to the tube exceeds 90 kv. may be employed.

While I have thus described my invention with specific 45 examples and applications, other modifications will be readily apparent to those skilled in the art without departing from the spirit and scope of the invention as defined in the appended claims.

What I claim is:

1. A device for controlling the potential of a source 50 comprising an X-ray tube coupled to said source, a secondary radiator containing at least one element of the periodic series which when exposed to X-radiation produced by said tube generates its characteristic X-ray spectra, means to detect the characteristic X-ray radiation produced by said secondary radiator, and means coupled to said detection means and responsive to the intensity of the characteristic radiation produced by said element for controlling the potential of said source.

2. A device for controlling the potential of a source 55 comprising an X-ray tube coupled to said source, a secondary radiator exposed to primary X-radiation produced by said tube and containing an element which generates its characteristic X-radiation in response thereto, means to detect the characteristic X-radiation produced by said element, and means coupled to said detection means and responsive to the intensity of the characteristic radiation

produced by said element for controlling the potential of said source.

3. A device for controlling the potential of a source comprising an X-ray tube coupled to said source, a secondary radiator exposed to primary X-radiation produced by said tube and containing a first element which generates its characteristic X-radiation in response thereto, a second secondary radiator exposed to said X-radiation and adapted only to scatter primary X-radiation incident thereon, means to detect the X-radiation obtained from said secondary radiators, and means coupled to said detection means and responsive to the intensity of the X-radiation produced by said secondary radiators for controlling the potential of said source.

4. A device for controlling the potential of a source comprising an X-ray tube coupled to said source, a secondary radiator exposed to primary X-radiation produced by said tube and containing an element which generates its characteristic X-radiation in response thereto, a second secondary radiator exposed to said primary X-radiation, a second specimen having an atomic number different than and adapted only to scatter primary X-radiation incident thereon, means to detect and produce an electrical quantity corresponding to the intensity of the characteristic X-ray radiation produced by said first secondary radiator, means to detect and produce an electrical quantity proportional to the intensity of the primary radiation scattered by said second secondary radiator, means coupled to both of said detection means for obtaining an electrical quantity proportional to the difference be-

tween the electrical quantities produced by said first and second detection means, and means coupled to said difference producing means and said source for controlling the potential thereof.

5. A device for controlling the potential of a source comprising an X-ray tube coupled to said source, a secondary radiator exposed to primary X-radiation produced by said tube and containing an element which generates its characteristic X-ray spectrum in response to said primary radiation, a second secondary radiator containing an element having an atomic number higher than said first element and adapted only to scatter primary X-radiation incident thereon, means to detect and produce an electrical quantity corresponding to the intensity of the characteristic X-ray radiation produced by said first secondary radiator, means to detect and produce an electrical quantity proportional to the intensity of the primary radiation scattered by said second secondary radiator, means coupled to both of said detection means for obtaining an electrical quantity proportional to the difference between the electrical quantities produced by said first and second detection means, and means coupled to said difference producing means and said source for controlling the potential thereof.
